UNITED STATES PATENT OFFICE.

GUSTAVE E. VILLARET, OF LEONIA, NEW JERSEY, ASSIGNOR TO HARRY HILFMAN, OF NEW YORK, N. Y.

DESIGN FOR A CANOPY RING FOR LIGHTING FIXTURES OR SIMILAR ARTICLES.

Application filed February 24, 1927. Serial No. 20,882. Term of patent 3½ years.

To all whom it may concern:

Be it known that I, GUSTAVE E. VILLARET, a citizen of the United States, residing in the city of Leonia, county of Bergen, and State of New Jersey, have invented a new, original, and ornamental Design for a Canopy Ring for Lighting Fixtures or Similar Articles, as shown, of which the following is a specification, reference being had to the accompanying drawing, forming part hereof, in which—

Figure 1 is an inverted plan view of a canopy ring for a lighting fixture showing

a general outline of the article, ornamented for a portion thereof.

Figure 2 is a side elevation of the same.

In Figure 1 I have shown the general outline of the article with only a portion thereof ornamented. The remainder of the article includes a repeat of the ornamented portion.

I claim:

The ornamental design for a canopy ring for lighting fixtures or similar articles, as shown.

GUSTAVE E. VILLARET.
